MANUFACTURE OF FOOTWEAR

Henry B. Gorman, Belmont, Mass., assignor to
Compo Shoe Machinery Corporation, Boston,
Mass., a corporation of Delaware

Application January 27, 1937, Serial No. 122,501

7 Claims. (Cl. 12—142)

This invention relates to the manufacture of footwear, and more particularly to the making of certain types of welted shoes.

In my copending application Serial No. 38,685, filed August 31, 1935, there is disclosed and claimed a novel method and shoe, wherein a welt is attached to a fastening strip to form a welt unit, the welt of which is attached around the margin of an outsole, and the fastening strip cemented to the underside of a lasted shoe. In my copending application Serial No. 50,070, filed November 16, 1935, a welt unit useful in assembling such a shoe is disclosed and claimed.

The present invention relates to shoes of this general type, and general objects of the invention are to provide improved and novel methods of manufacturing such shoes, and improved and novel shoe constructions produced in accordance with such methods.

More specifically, an object of the invention is to provide a novel method of assembly whereby the welt unit can be conveniently fitted and attached to the outsole by means of cement.

Further objects of the invention are to provide a shoe bottom assembly useful in making shoes of the type herein contemplated, a welt ply useful in making such bottom assembly, and methods of producing said bottom assembly and welt ply.

Other objects of the invention will in part be obvious and will in part appear hereinafter.

The invention accordingly comprises the several steps and the relation of one or more of such steps with respect to each of the others, and the article possessing the features, properties, and the relation of elements, which are exemplified in the following detailed disclosure, and the scope of the invention will be indicated in the claims.

For a fuller understanding of the nature and objects of the invention, reference should be had to the following detailed description taken in connection with the accompanying drawing, in which:

Fig. 1 is a transverse sectional view showing one stage in the construction of a welt unit used in carrying out the invention;

Fig. 2 is a transverse sectional view of the welt unit of Fig. 1 with its fastening strip in its final position;

Fig. 3 is a fragmentary sectional view through a portion of a welt ply constructed in accordance with the invention;

Fig. 4 is a top plan view, on a reduced scale, of the foot side of a shoe bottom assembly incorporating the welt ply of Fig. 3, parts being

broken away better to show the underlying construction;

Fig. 5 is a longitudinal vertical sectional view through a shoe bottom assembly made in accordance with the present invention and showing the welt ply of Fig. 3 being assembled with an outsole;

Fig. 6 is a fragmentary sectional view, on a scale corresponding with Figs. 1 to 3, showing an edge portion of a united shoe bottom assembly;

Fig. 7 is a transverse vertical sectional view across the shank portion of the shoe bottom assembly; and

Fig. 8 is a fragmentary longitudinal sectional view through the toe portion of a shoe embodying features of the invention.

In accordance with the invention disclosed in my previously mentioned applications, it is contemplated that the welt unit may be attached to the outsole either by means of cement or stitching. When the welt unit is stitched to the outsole, it is readily shaped to conform therewith by the ordinary material guiding elements on the stitching machine which position the welt along the margin of the outsole. When a cement bond is to be employed between the welt and outsole, however, it is difficult to shape the elongate welt unit to the marginal contour of the outsole and to hold it in such position during the pressing operation which is preferably employed while the cement sets.

In accordance with this invention, the welt unit is shaped to the outsole contour by a preliminary attachment to a shaping piece which may conveniently be a filler piece normally used in constructing the shoe. When thus shaped, the welt unit may readily be cemented to the outsole and proper registry between it and the outsole is readily provided while the elements are in a suitable cement-affixing press.

Referring more particularly to the drawing, there is shown in Figs. 1 and 2 a welt unit comprising a welt 10 of leather or the like, which may be of conventional size and construction for a given type of shoe, and which, preferably, has an inseam accommodating groove along its flesh side and an opposed bevel along the inner margin of its grain side, as illustrated. A fastening strip 11 is doubled along a fold line which is approximately registered with the inner edge of the welt. This fastening strip is preferably of strong fabric such as textile tape, canvas, or the like. Strong inseam stitching 12 passes through the inner margin of the welt and both doubled folds

of the fastening strip which latter may thereafter be undoubled as shown in Fig. 2 to present upwardly facing cementable surfaces extending both inwardly and outwardly from the 5 inseam.

A shaping piece 13 is provided which is preferably also a filler piece adapted to compensate for the welt thickness in the shoe bottom construction. This shaping piece may be of any suitable 10 material possessing sufficient stiffness to be adequately self-sustaining for its intended function, for example, heavy matted paper, "Onco", or any other suitable composition or fibrous sheet material, including leather. The shaping piece 15 13 is constructed in accordance with the size requirements of the outsole to be used in the particular shoe being assembled and its marginal edges as at 14 are shaped to follow the marginal outline of such given outsole but to be located inwardly therefrom a distance at least as great as and preferably approximately corresponding to the width of the welt 10. The piece 13 may conveniently terminate at approximately the heel breast line, or, if desired, it may substantially 20 overlie the entire outsole, and its thickness preferably corresponds with that of the welt 10.

The welt unit shown in Fig. 2 is attached around the margins of the shaping piece 13 in any suitable manner, for example, by means of stitches, 30 staples, adhesive, or the like, to form a unitary welt ply. Stitching 15 is preferably used for this purpose and serves to hold the inwardly extending portion of the fastening strip 11 down against the upper marginal surface of the shaping piece 35 13. Preferably, feather stitching or other stitching having a considerable lateral extent is employed to bind the fastening strip down flat against the shaping piece, and a loop of each stitch is preferably passed through the doubled 40 fold of the fastening strip as shown in Fig. 3 in order to hold the welt closely adjacent the edge of the shaping piece. The ends of the welt unit may desirably be continued rearwardly somewhat beyond the heel breast line and beyond the end 45 of the shaping piece, subject to subsequent butt ending, to facilitate preliminary registry of the welt and filler with the outsole in the manner about to be described.

An outsole 16 is provided which is preferably 50 rounded and shank-skived preparatory to assembly with the welt ply. This outsole may be of grain leather or other suitable material and is preferably amenable to cement bonding with the welt. The outer edges of the welt 10, which are 55 shaped by the margins of the shaping piece 13 to which the welt unit is attached will substantially coincide with the rounded edges of the outsole, and the welt ply is located over the outsole in such registered position. A preliminary locating 60 adhesive 17 is applied between the extreme rear portion of the welt ply, including the rearmost ends of the welt unit, and the outsole in order to hold the former in registered position. A strong permanent adhesive such as pyroxylin cement is 65 interposed between the welt ply and the outsole. This may be applied to the flesh side of the welt at any time prior to or during the construction of the welt unit, or it may be applied to the welt or the welt and shaping piece after the assembly 70 of the welt ply. Such cement also may be applied to the marginal portions or to the entire forepart and shank portion of the outsole. In each instance, it may either be applied and permitted to dry prior to assembly of the welt ply and out- 75 sole and then rendered adhesive by the applica-

tion of solvent just prior to such assembly or it may be applied wet just before assembly.

The welt ply and outsole, having permanent adhesive therebetween, and being located in registry as shown in Fig. 5, are preferably placed in a press and kept under pressure until the adhesive sets. This press may comprise opposed platens, if desired, and if a shank-skived or otherwise irregularly surfaced outsole is used, suitable accommodations therefore may be provided in one of these platens. If preferred, a yieldable pressing surface may be provided on at least one platen, and the presses may conveniently be routed around an endless carrier in accordance with well-known shoe pressing procedure. 15

After the welt ply and outsole are permanently affixed to each other, shown in Fig. 6, the shoe bottom assembly thus formed is preferably molded at the shank portion to approximate the under-surface of the lasted shoe, and the welt may also 20 be butted to end at the heel breast line.

A lasted upper is provided which may be of any suitable type capable of being joined with the shoe bottom assembly. A preferred form of shoe comprises an insole 20 having an upper 18 overlasted thereto with its lasting allowance in flat overlying relation therewith. Cement, tack, staple, or any other suitable form of lasting may be employed. If desired, an additional filler piece 25 19 may be located in the central forepart portion of the underside of the shoe bottom between the inturned edges of the lasting allowance, and if desired, a metal shank stiffener and other conventional appurtenances may be assembled with the lasted shoe. 30

The shoe bottom assembly as shown in Figs. 6 and 7 is now ready for cement attachment to the underside of the lasted shoe. To this end, the upwardly facing portions of the fastening strip 11 are coated with a suitable permanent adhesive 40 such as pyroxylin cement and the underside of the shoe is also preferably roughed and cemented. In each instance, this cement may be applied and allowed to dry prior to the bottom affixing operation, and may be rendered active by the application of solvent at the proper time. The bottom assembly is located on the underside of the lasted shoe with the cement properly activated and the entire shoe assembly is placed in a suitable sole-affixing press and held under pressure until the 50 cement sets.

In accordance with this mode of assembly, the welt can be conveniently and accurately attached to the outsole by means of adhesive. Certain benefits of the invention are also obtained even 55 when a stitched connection is employed between the welt 10 and the outsole, and it is contemplated that this form of connection may also be employed within the purview of the appended claims when the context permits. 60

Since certain changes in carrying out the above process, and certain modifications in the article which embody the invention may be made without departing from its scope, it is intended that all matter contained in the above description or shown in the accompanying drawing shall be interpreted as illustrative and not in a limiting sense. 65

It is also to be understood that the following 70 claims are intended to cover all of the generic and specific features of the invention herein described, and all statements of the scope of the invention which, as a matter of language, might be said to fall therebetween. 75

Having described my invention, what I claim as new and desire to secure by Letters Patent is:

1. In a method of making shoes, the steps comprising, attaching a fabric fastening strip to a free welt, to form a welt unit, then attaching said unit around the margin of a filler piece, thereafter adhesively attaching said welt to an outsole, and then adhesively attaching said fastening strip to the underside of a lasted shoe.
2. In a method of making shoes, the steps comprising, first stitching a fabric fastening strip to a free welt, providing an outsole, providing a filler piece with margins following but located inwardly from margins of said outsole, then attaching said stitched fastening strip to said filler piece with said welt located outwardly from the filler piece margins and with said strip overlying the outer margins on the foot side of said filler piece, thereafter adhesively uniting said welt and outsole, and then adhesively attaching said fastening strip to the underside of a lasted shoe.
3. In a method of making shoes, the steps comprising, stitching a fabric fastening strip to a free welt in position to extend inwardly therefrom, providing an outsole, providing a filler piece with a margin following but located inwardly from the margin of said outsole, then stitching the inwardly extending portion of said strip over the margin of the foot side of said filler piece with the inner edge of said welt positioned in butted relation with the outer edge of said filler piece, then adhesively attaching said welt to said outsole, and thereafter adhesively attaching said strip to the underside of a lasted shoe.
4. In a method of making shoes, the steps comprising first attaching a fabric fastening strip to a welt to form a welt unit, providing an outsole, shaping said welt to overlie the margins of said outsole by attaching said fastening strip around the edges of a sole shaped sheet while positioning the inner edge of said welt in butted relation with the outer edges of said shaped sheet, adhesively uniting said shaped welt and outsole, and then adhesively attaching said fastening strip to the underside of a lasted shoe.
5. In a method of making shoes, the steps comprising, stitching a fabric fastening strip along the inner side of a welt to form a welt unit, providing a rounded and shank skived outsole, providing a sole shaped sheet with a margin following but located inwardly from the margin of said outsole, stitching said fastening strip above the margin of said sheet while drawing the inner edge of said welt into butted relation with the outer edge of said sole shaped sheet to shape said welt to the sole, interposing adhesive between said welt and sole, pressing said welt and sole together until said adhesive sets to form a bottom assembly, molding said bottom assembly, and thereafter adhesively attaching said fastening strip to the underside of a lasted shoe.
6. In a method of making shoes, the steps comprising, providing a rounded outsole, providing a filler piece with guiding edges following but located inwardly from the margins of said outsole, stitching the outer portion of a fabric fastening strip to a free welt with its inner portion extending inwardly from the welt, then attaching the inwardly extending portion of said strip above the margin of the foot side of said filler piece while drawing the inner edge of said welt into butted relation with the guiding edges of said filler piece to form an intermediate welt ply, and then cementing said welt ply and outsole together to form a welted shoe bottom assembly adapted thereafter to have the exposed portion of the fabric strip cemented to the bottom of a shoe.
7. A shoe bottom assembly arranged as a unit adapted for subsequent cement attachment to a lasted shoe and comprising, a rounded outsole, a welt having a fabric fastening strip stitched thereto and extending inwardly therefrom, a filler piece overlying said outsole and having its edges terminating short of the sole edges by approximately the width of said welt, said welt overlying and being adhesively attached to the marginal portion of said outsole outwardly from said filler piece with its inner edge positioned in butted relation with the outer edges thereof, and stitching joining said fastening strip and filler piece, the inwardly extending portion of said fabric fastening strip being located above the foot side of said filler piece and providing a cementable surface adapted to be adhesively attached to the bottom of said lasted shoe.

HENRY B. GORMAN.
